UNITED STATES PATENT OFFICE.

FRANZ WELS, OF VIENNA, AUSTRIA.

POWER-TRANSMISSION MECHANISM.

Application filed December 2, 1921. Serial No. 519,539.

To all whom it may concern:

Be it known that I, FRANZ WELS, of No. 31 Schoenburgstrasse, Vienna, IV, Austria, a citizen of the Republic of Austria, have 5 invented some new and useful Improvements in and Relating to a Power-Transmission Mechanism, of which the following is a specification.

The present invention, which has originated from exhaustive studies of the kinematic deflection of a fish's tail, consists of the mechanical solution of the problem and its technical application as an active propulsion or hydrodynamic driving mechanism, or also as a stationary active machine 15 in any desired medium, whether it be solid, semi-solid, gaseous, or liquid, or of an atmospheric or energetic character.

The local movement of the fishes, is effected by the vertebral mechanism, which, comparable with a running capsule mechanism by diagonally produced muscular contractions, causes bending of the body (Fig. 1) and which, always commencing at the 20 head, are directed backwardly and, before they entirely cease with the unequal caudal fin, again recommence at the front. If two or more such impulses simultaneously flow through the vertebral column, then the 25 result is the sinuous diagram according to Figure 1, in which e , e' , e'' indicate the thrust trajectories, the arrows their directions and R the resultant movement to the front.

In a similar manner the oblique position of the broad sides takes place in the case of the segmentally moved wings of birds, the inceptive point e of which in the same 30 sinuous scheme V now lies upon the line A—B and the extreme sweep m , n , of which represent the wave crest and wave trough; the difference between the wing and the fish-tail consists solely in the fact that the former is only influenced on one side.

From the point of view of research, fish and bird belong together and the latter has evolved from the former, passing through the reptile family, hence also the relationship of this mechanism, it being immaterial if it 45 be actuated in an equal or unequal manner, segmentally oscillating or whether vertical or horizontal, the principle remains the same, and this function of oblique positioning also extends to insects and hymenopterae.

All these bio-mechanic processes are based

upon the wave (Figure 1), the archetype of the inorganic world, the temporary abb of which is the graphic expression of all these movements.

Exhaustive, systematic experiments to design a mechanical movement of equal value have resulted in the arrangement shown in the accompanying drawings in which:

Figure 1 is a diagrammatic illustration of the movement of a fish.

Fig. 2 is a plan or lateral elevation of one embodiment of the present invention, the dot and dash lines indicating the different positions successively assumed by the driving element W , while there is also illustrated diagrammatically a plurality of such elements.

Fig. 3 is a side elevation of the apparatus, and

Fig. 4 is a similar view in the direction G—E, Fig. 2; the same being shown partly in section.

Referring now, more particularly, to the accompanying drawings, there is provided 80 a guide Z in which is journaled a shaft carrying the crank or eccentric K , the outer end of which is pivotally connected with a connecting rod P . The opposite end of this connecting rod P is arranged perpendicular 85 to and rigidly connected with one surface of driving element or plane W , while the attaching point of the rod P is spaced about a third of the length of the plane of the forward edge thereof. In this connection 90 it may be stated that the surfaces of the plane are tapered toward their respective ends as indicated, while the rear end is formed of resilient material. The middle portion of the plane is journaled in a cross 95 head slide which operates between the guide Z .

By reason of the foregoing arrangement, when power is applied the crank K and rod B coact with the guiding means Z so that 100 the plane W will describe alternating positive undulatory oscillations.

In both cases, commencing from either of the two dead point positions O , O' (wave crest or wave trough) the head points or 105 crest summits L first of all swing in, pass by way of a translation L^1 , L^2 , L^3 with the angles B , constantly becoming flatter over the highest accelerated nodal point X and terminate with an active rearward sweep, 110 in order to again immediately set in at the front in the contrary direction and to re-

turn to the initial position O, whilst permanently upholding the pressure action D, which is always approximately perpendicular to the driving organ W and hence at 5 the same time relieves the cross head guides. In this case a prejudicial frontal resistance does not take place, as the longitudinal planes f—g and h—i are not exceeded with a correct adjustment and low resilient termination similar to the fish's tail and to the wing of the bird, which will be apparent from the drawing, in which the driving member successively adopts the position L¹—t¹, L²—t², L³—t³, etc., shown in dotted lines.

10 The crank mechanism, the thrust rod of which may be extremely short in this case, by its alternative movement renders possible the ambi-lateral or also uni-lateral throw 15 of the medium substance upon the driving member according as to whether the system is assumed to be immersed or suspended in space.

15 The path areas here, however, are not twice the diameter d , but rather through 20 the angle of inward and outward swing B, B' the entire circular surface is converted into plane sectors, whilst also the velocities v not only add themselves together through 25 the above mentioned transverse outward rotations, but also give a perfectly uniform movement of the drive and a backward displacement of particles in space, i. e. the resultant of the total forward movement of 30 the whole. In its movement of inversion the system can also be actuated as a retrograde 35 motion device.

40 Instead of one driving surface there may also be several, always standing perpendicular to the connecting line c—b of the thrust rod P, arranged either directly upon this latter or beyond its poles.

45 Besides the prism guide shown any other known rod guide or transmission by means of cranks arranged in pairs and also by hypocycloidal sliding circular guides may be used. On the other hand the connecting rod, guided on the one hand in a circular and on the other hand on a straight line, may 50 only serve as a kinematic guide for the translation and the dynamic movement may be obtained direct through a straight piston.

55 This driving mechanism obtains its special development in the principle of crank formation (Figure 2) in that the fundamental element W is positively connected by guide shoulders F, F', F'', F''', with further similar or larger similar elements W',

W'', W''', which participate in the movements on the straight line E—G at any desired distances, guided upon a common slide Z, Z' and also passing beyond the crank point W'''.

60 According to the purpose in view, all these drives may be arranged horizontally, vertically, or obliquely axially, also placed in pairs opposite each other or swinging parallelly, above, beside or behind each other in uniform or differentiated groups. If arranged in pairs the non-symmetry of the 65 paths in the crank drive will be removed and the rotary moments will be compensated for.

70 The laws thus found, as illustrated by comparative mechanism, are represented in the screw, which coincides with the wave not only planimetrically but also in its spherical development.

75 The sum total deduced from all the comparisons is found in the above translation element combined not only kinematically but also dynamically with the special feature that actuated in a plastic flood and avoiding cavitation a better utilization is secured of the Rankin after-flow N in Figure 2, and the theoretical difference that the positive course of the oblique plane does not take place in rotation but in a translatory phase reversal.

80 Having now particularly described and ascertained the nature of my said invention and in what manner the same is to be performed, I declare that what I claim is:

85 1. Mechanism of the character described including guiding means, an oscillatory propeller blade mounted for sliding movement in said guiding means, a rotating crank, and means operatively connected with the crank and rigidly connected with the blade for positively reciprocating the blade so that 90 it will describe alternating undulatory oscillations.

95 2. Mechanism of the kind defined by claim 1, wherein the blade has its rear portion elongated and formed of resilient material.

100 3. Mechanism of the character described including in combination, spaced paralleled guides, a head slidable therein, a resilient blade-like element mounted medially of its ends for oscillation in the head, a rotating crank mounted in said guides, and a connecting member pivoted to the crank and rigidly connected with the element for reciprocating the element so that it will describe alternating undulatory oscillations.

110 In testimony whereof I have signed my name to this specification.

ING. FRANZ WELS.
